JACOB WEISENBERGER, OF CORNING, NEW YORK, ASSIGNOR TO CORNING GLASS WORKS, OF CORNING, NEW YORK, A CORPORATION OF NEW YORK.

INITIAL-PUFF MECHANISM FOR GLASS-BLOWING MACHINES.

1,410,857.

Specification of Letters Patent. Patented Mar. 28, 1922.

Application filed March 14, 1921. Serial No. 452,101.

To all whom it may concern:

Be it known that I, JACOB WEISENBERGER, a citizen of the United States of America, and a resident of Corning, New York, have invented certain new and useful Improvements in Initial-Puff Mechanism for Glass-Blowing Machines, of which the following is a specification.

In Letters Patent No. 1,124,701, issued 10 on an application of Benjamin D. Chamberlin for "an apparatus for the production of blown glass articles", there is disclosed means whereby an air pump is actuated from time to time to force air into a marvered 15 blank on the end of a glass carrying blow-pipe to expand the same, the actuation of the pump, for the purpose stated, following a movement of the blow-pipe from the marvering position.

20 My invention relates to a device designed to be attached to such apparatus, and to actuate the pump previous to the movement of the blow-pipe from marvering position for causing the initial puff.

25 In the accompanying drawings:—

Figure 1, is a fragmental front-elevation of the main cam and its mounting, of the machine disclosed by Letters Patent No. 1,124,701, showing the blow-pipe frame in 30 horizontal position with the blow-pipe held therein, and certain parts of the air mechanism, my invention being shown applied thereto;

Fig. 2, is an enlarged elevation partly in 35 section, taken at right angles to Figure 1, and

Fig. 3, is a fragmental plan view.

Referring to the drawings, the blow-pipe is pivotally mounted by means of a 40 triunion 2 for oscillation in a bearing 4. A cam disk 6 is also pivotally mounted concentric to the triunion. One of the functions of the cam disk is to impart movement to the blow-pipe frame to raise the same to a 45 position for marvering glass on the end of a blow-pipe 3 therein, and to move it away from such position. The direction or rotation of the cam disk is indicated by the full line arrow in Figure 1.

50 Mounted in the same plane as the cam disk 6, is a stationary cam plate 7, which, as shown, is a sector concentric with the cam disk. This sector carries a series of radially adjustable cams 8, 9, 10, 11, and 12, and a 55 series of crown tip projections 13, 14, and

15, the rises of the series of cams being radial in respect to the axis of oscillation of the blow-pipe frame, while the rises of the projections are at right angles to such plane.

16 The blow-pipe frame comprises a skeleton extension formed by pipes 16 and 17, that carry an air cylinder 18. The cylinder is designed to receive one end of the blow-pipe 3, means being provided for sealing the 20 two to prevent escape of air, and passing through the head of the cylinder is a piston rod 19, the inner end of which has slidably mounted thereon a piston 20, the rod being surrounded by a spring 21 that forces the 25 piston forwardly. The piston rod 19 has upon its outer end and upon the outside of the cylinder a conical head 22 with which a laterally extending finger 23 on the outer end of a cocker rod 24 slidably mounted in 30 the blow-head casting and in bearings on the body of the blow-pipe frame, is adapted to engage.

35 The inner end of the cocker rod is provided with a foot block 25, carrying a roller 26, adapted to contact with and be lifted by the cams 8, 9, 10, 11, and 12, and has also attached thereto a laterally extending arm 27, having on the end thereof a roller 28, adapted to contact with the projections 13, 14, and 15, on the cam plate whereby the rod will be given an angular motion.

40 The rod 24 has thus two motions in its bearings, the one longitudinal, which, when the finger 23 is in engagement with the head 22 on the piston rod, retracts the latter, and the other an angular or rotary movement, which disengages such finger from the head on the piston rod and permits the spring 21 to project the latter forwardly.

45 Parts similar to those above described are present in the aforesaid Patent No. 1,124,701, and hence need no further description.

50 Mounted on the cam plate 7, by means of a bracket 31, is a rock-shaft 32, having a laterally extending arm 33 at its outer end and a laterally extending arm 34 at its inner end. At the outer end of the arm 33 is a roller 35, while at the outer end of the arm 34 is a 55 plate 36 that normally lies in a recess 37 formed in the cam plate 7. A headed stud 38, threaded to the plate 36 and passing through an opening 39 in the cam plate 7 is encircled by an expandable spring 40, this construction being such that the plate 36 60

will be retained within the recess 37 by the spring 40.

The relative position of the plate 36 on the outer end of the arm 34 with respect to the 5 roller 28 on the outer end of the laterally extending arm 27 of the cocker rod 24, is such that when the blow-pipe frame is in marvering position, the roller 28 is over the plate 36, and in contact therewith.

10 As in Patent No. 1,124,701, the rotation of the cam disk in the direction of the full line arrow causes a reverse motion (see dotted arrow Figure 1) of the blow-pipe to marvering position, a pause of the blow-pipe at that position and finally a retrograde motion of the blow-pipe.

At the completion of the marvering operation, the relative position of the cam disk is such that a stud 5 on the face thereof will, 20 on continued motion of the cam, engage roller 35 on the outer end of the laterally extending arm 33 of the shaft 32, and so doing will raise the arm 33, causing the shaft 32 to be rotated, and thereby raising plate 36

25 against the tension of spring 40, to the dotted line position shown in Fig. 2 of the drawings. By preference this is timed to occur before the blow-pipe frame has been moved from marvering position.

30 When plate 36 rises, it carries roller 28, thereby turning the cocker rod 24. This will cause the finger 23 on the outer end of the rod 24 to be moved from its engagement with the head 22 of the piston rod 19. Inasmuch as the rod 24 was prior to this time and 35 on the movement of the blow-pipe to marvering position, moved outwardly by the cam 8 (see Figure 1) the release of the piston by the rod results in the spring 21 causing the piston to move forward in the cylinder, and in a puff of air being forced into the marvered blank on the outer end of the blow-pipe, as will be readily understood.

The movement of the parts to create the 45 puff in the blow-pipe is momentary, and the continuing motion of the cam disk 6 carries the stud 5 past roller 35, and the parts are returned to their normal positions, the plate 36 returning to its seat within the recess 37

50 in the cam plate 7. The blow-pipe frame is then set in motion, and the roller 28 will ride off plate 36 directly on to the face of the cam plate 7, and will, as the blow-pipe frame swings to vertical position ride over the projections 13, 55 14, and 15 to produce other puffs of air in the blank, as is described in the aforesaid patent.

It will be noted that whereas the former 60 patent required a movement of the blow-pipe frame in respect to the fixed cam plate 7 to cause the initial puff, this invention causes such puff by relative movement between the blow-pipe and the movable cam disk 6. This difference permits the puff to

follow the marvering more quickly and to take place while the blank is still in marvering position instead of after it is moved therefrom.

Having thus described this invention what I claim is:—

1. In a device of the character described, the combination of a movable blow-pipe frame, a cam movable in respect to the frame, an air pump, and means for actuating such pump by the movement of the cam without substantial movement of the blow-pipe frame.

2. In a device of the character described, the combination of a movable blow-pipe frame, a cam movable in respect to the frame, a spring actuated air pump, means actuated by the movement of the frame for cocking the pump, and a trigger mechanism for releasing the pump controlled by the movement of the cam in respect to the blow-pipe frame while the latter is substantially stationary.

3. In a device of the character described, the combination of a blow-pipe frame movable to and from a position for marvering a gather of glass carried thereby, a cam movable in respect to the frame, an air pump, and means for actuating such pump by the movement of the cam while the blow-pipe frame is in marvering position.

4. In a device of the character described, the combination of a blow-pipe frame movable to and from a position for marvering a gather of glass carried thereby, a cam movable in respect to the frame, a spring actuated air pump, means actuated by the movement of the frame for cocking the pump, and a trigger mechanism for releasing the pump controlled by the movement of the cam while the blow-pipe frame is in marvering position.

5. In a device of the character described, the combination of a movable blow-pipe frame, a cam movable in respect to the frame, a spring actuated air pump, means actuated by the movement of the frame for cocking the pump, a trigger mechanism for releasing the pump, a stationary cam plate, and means carried by the cam plate for releasing the pump, said means being actuated by the movement of the cam in respect to the blow-pipe frame while the latter is substantially stationary.

6. In a device of the character described, the combination of a blow-pipe frame, a cam movable in respect to the frame, a spring actuated air pump, a stationary cam plate having means actuated by the movement of the frame for cocking the pump, a trigger mechanism for releasing the pump, and means carried by the cam plate for releasing the pump by the movement of the cam in respect to the blow-pipe frame.

7. In a device of the character described,

the combination of a blow-pipe frame, a cam movable in respect to the frame, a fixed cam plate, a spring actuated air pump for injecting an air puff into a gather of glass carried on the end of a blow-pipe in the frame, means actuated by the movement of the frame for cocking the pump, a trigger mechanism for releasing the pump, a rock- shaft mounted on the cam plate and having a laterally extending arm in engagement with the trigger releasing mechanism, and means for actuating the rock-shaft by the movement of the cam in respect to the blow-pipe frame.

JACOB WEISENBERGER.
